Specification for Design.

Patented Jan. 17, 1911.

Application filed November 16, 1910. Serial No. 592,740. Term of patent 7 years.

To all whom it may concern:

Be it known that I, WILLIAM F. BROWN, a subject of the King of Great Britain, residing at New York city, in the county of New York and State of New York, have invented a new, original, and ornamental Design for a Rug, of which the following is a specification, reference being had to the accompanying drawing, forming part thereof.

The drawing illustrates one quarter of a rug showing my new design, the remaining three quarters being duplicates thereof.

I claim:

The ornamental design for a rug, as shown.
